CLAIM

The ornamental design for a tripod for cameras, as shown and described.

DESCRIPTION

FIG. 1 is a perspective view of a tripod for cameras according to my new design, in a closed configuration;
FIG. 2 is a front view of the tripod of FIG. 1;
FIG. 3 is a left side view of the tripod of FIG. 1;
FIG. 4 is a rear view of the tripod of FIG. 1;
FIG. 5 is a right side view of the tripod of FIG. 1;
FIG. 6 is a top view of the tripod of FIG. 1;
FIG. 7 is a bottom view of the tripod of FIG. 1;
FIG. 8 is a bottom view of the tripod according to my design in an open configuration;
FIG. 9 is a top view of the tripod according to my design in open configuration;
FIG. 10 is a front view of the tripod according to my design in an open configuration;
FIG. 11 is a right side view of the tripod according to my design in an open configuration;
FIG. 12 is a left side view of the tripod according to my design in an open configuration; and,
FIG. 13 is a FIG. 13 is a rear view of the tripod according to my design in an open configuration.
The broken lines in the drawings are intended to show environmental structure and form no part of the claimed design.
